Application filed May 21, 1900. Serial No. 17,485. Term of patent 3½ years.

To all whom it may concern:

Be it known that I, WILLIAM T. PARTRIDGE, a citizen of the United States, residing in New York, in the borough of Manhattan, county 5 and State of New York, have invented and produced a new and original Design for a Cover for a Pen-Wiper or other Article, of which the following is a specification, reference being had to the accompanying drawings, forming a part hereof.

As shown in the drawings, the leading or material feature of my design consists of the cover provided with a miniature bottle, un-

corked and lying on its side, (represented by a ,) and a series of irregular lines and blots radiating from the mouth of the bottle in 20 imitation of streams and pools of fluid, (represented by b .)

Having described my invention, what I claim as new, and desire to secure by Letters Patent, is—

The design for a cover for a pen-wiper or similar article, as shown and described.

In testimony whereof I have signed my name to this specification in the presence of two subscribing witnesses.
